UNITED STATES PATENT OFFICE.

EARL G. BENNETT, OF CHICHESTER, NEW YORK.

SUPPORTING STRUCTURE FOR TYPEWRITERS, ADDING MACHINES, BOOKKEEPING MACHINES, AND THE LIKE.

Application filed June 6, 1927. Serial No. 196,777.

This invention relates to new and useful improvements in supports for typewriters, bookkeeping machines, adding machines, and other similar devices used in offices, banks, 5 and business houses, and aims to provide a mechanism of this character that is readily adaptable for incorporation within a desk, the structure being such as to permit the machine to be readily raised or lowered so that 10 when in lowered position, the top of the desk which is of the hinged variety, may be closed for obviously permitting the surface of the desk to be used for other purposes.

Furthermore, one form of the invention 15 consists of a means adaptable directly to the desk lid so that when the lid is swung into open position, the machine will be automatically raised, whereas upon the closing of the lid, it will be automatically lowered. However, 20 it is not absolutely necessary that the mechanism be directly attached to the lid, as foot or hand means may be provided for facilitating the raising and lowering of the machine.

25 In this instance however, a counter-balancing weight is employed in lieu of the desk lid which in that instance acts as a counter-balancing medium.

By reason of the present invention, the machine 30 is always supported in a vertical position and is not tilted over to an angular position within the confines of the desk when not in use.

Structures of this character permit little 35 or no leg room beneath the desk when the same is being employed for the assortment of papers, writing, etc.

In the drawings wherein there is disclosed two embodiments of the present invention:

40 Figure 1 is a fragmentary section through a generally conventional design of desk, equipped with my improved supporting means, in this instance, the lid of the desk being actually associated with the mechanism, whereby when the lid is raised, the machine will be automatically elevated, whereas on the other hand, when the lid is lowered, the machine will be also lowered.

45 Fig. 2 is a similar view disclosing the desk lid in open position and the mechanism hav-

ing been actuated to raise the typewriter to the top of the desk.

Fig. 3 is a front elevation of the mechanism as disclosed in the typewriter supporting board being partially disclosed in cross section, for indicating the means whereby the rear end of the board is attached to certain units of my device, and

Fig. 4 is a view similar to Fig. 1, disclosing the device as associated with a desk having 55 an ordinary hinged lid, the mechanism in this instance being operable by a foot lever, and in this instance, a counter-balancing weight being provided in lieu of the desk lid, disclosed in Figs. 1, 2 and 3, which as previously stated performs the function of a counter-balancing weight.

First having particular reference to Figs. 1, 2 and 3, A will designate the generally conventional design of desk wherein the top thereof is provided with a hinged lid B, the front side of the desk being open within the length of the lid as generally suggested in Fig. 3.

In this particular construction of supporting device, the hinge connection between the rear edge of the lid B and the top of the desk at the edge of the opening, is removed.

The supporting mechanism per se, consists of a lazy-tong structure arranged within the desk A, at opposite sides of the front opening therein, each lazy-tong structure being of identical elements, therefore a description of one will suffice for both.

Pivots interconnected as at 5 which pivot is fixed to the adjacent side of the desk opening, and intermediate the ends thereof, is a pair of elongated cross bars 6 and 7. Pivots connected to the lower ends of these cross bars are vertically extending links 8 and 9, the rearmost link being slightly shorter than the foremost one, as indicated in Figs. 1 and 2.

The upper ends of these links 8 and 9 are pivotally attached to inwardly extending 95 bars 10 and 11, which bars are pivoted adjacent their inner ends to fixed pivots 10' and 11', the pivot 10' of the rearmost bar 10, being slightly above the pivot 11', again see Figs. 1 and 2.

The length of the bar 10 is greater than that of the bar 11 so that the inner end of said bar 10 will extend beyond the inner end of the bar 11, while pivotally interconnecting the inner ends of said bars, is a short link 12. The lower end of the bar 10 extends beyond the end of the link 9 to which it is pivoted and pivoted to the extreme inner end of said bar 10, is an upwardly extending short link 13.

10 Pivotedly supported by fixed pivot 14, above the bar 10 in back of and slightly below the fixed pivot 10' of the bar 10, is the lower rearwardly extending end of an elongated upwardly extending L-shaped lever 15, the 15 upper end of which has pivotal connection as at 16 to a bracket 17 arranged upon the bottom side of the desk lid B in slight spaced relation with the forward edge thereof. The extreme lower end of this L-bar 15 is pivotally connected to the upper end of the link 13 so that when the L-bar is swung upon its pivot, 14, a direction indicated in Fig. 1, to that indicated in Fig. 2, the bar 10 will be swung at its inner end in a downward direction upon its pivot 10' while the connection between the bar 10 and the bar 7 will cause the upward swinging of the outer end of said bar 7.

10 Pivotedly secured to the upper ends of the 20 cross bars 6 and 7 are similarly inwardly converging and cross bars 18 and 19 pivoted at their cross points as at 20.

The bars 7 of the lazy-tong structures at opposite sides of the desk openings are interconnected by an adjustable length bar 21, and this at a point intermediate the fixed pivots 5 and the connecting links 9 between the bars 7 and 10. This interconnecting bar will serve to brace the lazy-tong structures at 35 opposite sides of the opening and cause the elements of the structure at opposite sides to move in unison.

Further at the pivotal points between the 40 upper cross bars 18 and 19, of the two lazy-tong structures, said bars 18 and 19 are interconnected by an adjustable cross bar 22 for further bracing the units and to assist the bar 21 in causing the elements of the units to move in unison.

50 Pivoted to the upper ends of the uppermost bars 18 at the lazy-tong units at opposite sides of the desk opening, are depending L-shaped brackets 23 to which is rigidly secured the horizontally extending machine supporting board 24. The upper ends of the cross bars 19 have pivotal connection with the depending L-shaped brackets 25, each of which is equipped with an inwardly extending roller 26, upon which the adjacent edge of the board 24 is 55 supported, see Fig. 3, this connection between each of the bars 19 and the board, permitting the upper ends of the bars to move inwardly and outwardly during the raising or lowering of the machine, but yet to support the 60 board in horizontal position.

Obviously, when the lid B of the desk is closed as indicated in Fig. 1, a lifting of the same at its forward end will cause the same to rise and then drop downwardly between the desk and as soon as the lid B passes in back 70 of the fixed pivot 14 of each L-shaped bar 15, the weight of the lid will serve to prevent the collapsing of the lazy-tong structures and the consequent dropping of the machine disclosed in dotted lines in Fig. 2 and designated 75 by the reference character C.

In the form of the invention indicated in Fig. 4, the L-shaped bars 15 of the lazy-tong structures are dispensed with while in this instance, the fixed pivot 10'a for the bar 10'a, 80 is arranged below the fixed pivot 11'a of the bar 11'a. In this instance also, the connecting link 8'a between the ends of the bar 11'a, and the forward cross bar 6'a, extends at its lower end beneath the pivot connection to 85 the bar 6'a, formed with an outwardly extending curved foot plate 27'a.

Depending from the pivotal connection between the link 13'a, which in this instance is slightly longer than the link 13 in the other form of the invention, and the cross bar 7'a 90 is a hanger 28'a that carries removable weights 29'a.

In this form of the invention, the lid B'a is hinged at its rear edge to the top of the 95 desk as clearly disclosed. Obviously, when the machine is in lowered condition, a pressure in a downward direction upon the foot pedal 27'a will cause the expansion of the lazy-tong structures, two of such structures being 100 also applied in this form and the consequent raising of the machine C'a, at which position, it will be held by reason of the counterbalancing weights 29'a.

It will thus be seen that I have provided 105 two highly novel, simple and efficiently operating types of supporting devices for typewriters, bookkeeping machines, and the like, for installation within an office desk, and even though I have herein shown and described 110 these forms as consisting of certain detail structural elements, it is nevertheless to be understood that some changes may be made therein without affecting the spirit and scope 115 of the appended claim.

Having thus described my invention, what I claim as new is:

In a disappearing support for desks of the character described, in combination with the usual rearwardly movable desk top, a support adapted to support a typewriter or similar machine, a pair of lazy tong structures upon which the support is adapted to rest, said structures having their respective upper ends associated with the ends of the machine support, a rearwardly disposed arm at the top of each lazy tong structure, a forwardly disposed arm at the top of each structure, the rearwardly disposed arms being pivotally connected with the rear portion of the 120 125 130

machine support, while the forwardly disposed arms are in slidable supporting relation with the forward portion of the support, the pivotal connection of the lower tong structure being connected with the desk structure, a pair of bars pivotally connected together at one of their ends, while their opposite ends are connected to the lower extremi-

ties of the respective lazy tong structure, and a pair of L-shaped levers pivotally connected at their intermediate portions to the desk structure, the upper ends of the levers being connected to the desk top, while the lower ends thereof are connected to the pivotal bars.

In testimony whereof I affix my signature.

EARL G. BENNETT.
